TWIN CYLINDER STEAM ENGINE

John M. Shimer, Dallas, Tex., assignor to Wilson-Snyder Manufacturing Corporation, Braddock, Pa., a corporation of Pennsylvania

Application April 9, 1935, Serial No. 15,477

2 Claims. (Cl. 121—194)

This is a continuation in part of my co-pending application Ser. No. 531,715 filed April 21, 1931.

This invention relates to twin cylinder steam engines and, more particularly, to steam engines of the double acting type having twin cylinders cast together as a single casting.

The problem of maintaining the parts of a twin cylinder steam engine in alinement and to obtain a compact engine has made it desirable to cast or otherwise form as many of these parts integral as possible. The forming of the parts integral has, however, been attended by considerable difficulty; since the metal of which the parts are made expands upon heating; and unless all of the parts are heated equally, the alinement between the parts is not maintained. A still further complication is introduced when the steam intake manifold and the exhaust manifold are also formed integral with the steam cylinders.

My invention overcomes these various objections and provides a steam engine in which inequalities of expansion may be absorbed and alinement insured at working temperatures.

The various features of my invention are illustrated in the accompanying drawings, in which:—

Fig. 1 is a view, partly in elevation and partly in central vertical section, of a vertical double acting steam engine embodying my invention and having twin cylinders cast together as a single casting; Fig. 2 is a view principally in elevation of a steam engine of the type shown in Fig. 1, parts being omitted for the sake of simplicity, so as to better illustrate my invention; Fig. 3 is a section on the line 3—3 of Fig. 2; Fig. 4 is a horizontal section through the steam intake manifold taken on line 4—4 of Fig. 1; Fig. 5 is a horizontal section through the exhaust manifold taken on line 5—5 of Fig. 1, and Fig. 6 is a view in elevation of a modified form of my invention with a power take-off at one end of the crank shaft, and with a floating outboard bearing, parts being broken away to facilitate illustration.

In the preferred embodiment of my invention shown in Figs. 1, 2, 3, 4, and 5, the steam cylinders 7 and 8 are integral with steam intake manifold 9 and with steam exhaust manifold 10 and hence with each other. Frame 11 is cast integral with bearing supports 13 and is divided in its lower portions, leaving between the two divisions an open space 12. Within each division is disposed a support 13 for one of the main bearings of the engine. By means of webs 14, 15, and 16, the support 13 is braced so that it is rigid with

the frame 11. Between the webs 14 and 15 is a stiffening web 17 and between the webs 15 and 16 is a similar web 18. Webs 19 and 20 extend upwardly from the webs 14 and 16, respectively. The web 19 does not cooperate directly with the support 13, while the web 20 does directly and rigidly brace the support 13. The support 13 is in the form of a ring surrounding the main bearing; and a minor portion of this support, indicated by the numeral 21, is flexible so as to permit clamping within the same of the housing 22 of the main bearing. The ring shaped support 13 is split at 23, as shown in Fig. 3. The two parts of the clamp are provided with openings through which extends a stud 24. Nuts 25 on the two ends of the stud may be drawn up to clamp the housing 22 within the support 13. Bearing support 13 also can be widened by inserting a wedge in opening 23 in order to facilitate the assembly of the crank shaft with the frame 11, so that the main bearings may be received within the bearing supports 13.

The main bearings are constituted by roller bearings 26. In order that the crank shaft 27 may be assembled with the frame, so as to be rotatably supported by the roller bearings 26, the cranks 28 are made separate from the shaft 27. Openings 29 are provided in the frame 11 in alinement with the main bearings, these openings 29 being supplied with cover plates 30. The crank shaft 27 extends across the space 12 through openings 31 in the frame 11, these openings being supplied with apertured cover plates 32. It will be apparent that inasmuch as the cranks 28 are made separate from the crank shaft 27, it is possible to mount the races of the roller bearings 26 on the shaft 27. The assembly of the crank shaft and roller bearings may be positioned within the supports 13; and by means of the studs 24 and nuts 25, the housings 22 of the roller bearings 26 may be secured in position. The cranks 28 may be pressed onto the crank shaft 27. In the embodiment shown, keys 33 secure the cranks 28 to the shaft 27.

The pistons which are reciprocable within the cylinders 7 and 8 are connected to cross-heads 34, reciprocable in cross-head guides 35. I prefer to form these guides 35 integral with the frame 11. Due to the greater extremes of temperature to which the steam end of the engine is subjected, the integral construction provided by my invention might lead to misalinement of the parts, if the cylinders 7 and 8 were in direct alinement with the cross-head guides 35 when the

entire structure is cold. For this reason, I bore the cylinders 7 and 8 on axes slightly offset toward each other, with respect to the cross-head guides, the amount of offset being sufficient to cause the 5 cylinders 7 and 8 to be brought into alinement with the cross-head guides 35 by expansion of the metal when heated up during operation of the steam engine. In Fig. 2, the center line of the cylinder 8 is indicated by the line *a* and the center 10 line of the cross-head guide 35 is indicated by the line *b*. As indicated in Fig. 2, these lines are slightly offset when the structure is cold. As the engine heats, the cylinders slide into alinement, sufficient clearance 35' being provided about the 15 bolts securing the cylinders to the frame to permit this movement of the cylinders (Fig. 1).

Between the cross-head guides and the cylinders 7 and 8 are spacers 36. In the embodiment shown, these spacers are integral with the frame 20 11, thereby avoiding opportunity for the cylinders 7 and 8 to get out of alinement after the same have been machined.

I further prefer to form the steam intake manifold 9 and the steam exhaust manifold 10 integral with the cylinders 7 and 8. In the embodiment shown, the cylinders 7 and 8 are double acting and are provided with ports 41 and 42 at the two ends of the cylinders respectively. A piston valve 37 cooperates with the steam intake 25 manifold, the exhaust manifold and the ports 41 and 42 to control the operation of the steam engine, this valve being actuated by suitable valve gear 38. A cylinder head 39 closes the top of each of cylinders 7 and 8, while a cylinder head 40 30 closes the bottom of each. The assembly of the cylinder block and the cylinder heads is bolted to the spacers 36, which in the embodiment shown are integral with the frame 11.

Since the metal in the steam intake manifold 40 and in the exhaust manifold is subject to a very substantial variation in temperature, and since the cylinders 7 and 8 and the steam intake manifold and the exhaust manifold are formed integral, the expansion of the metal, resulting from 45 the heating up of these parts, presents a difficulty in maintaining alinement of the cylinders. Accordingly, I provide in the steam intake manifold 9, a bend 43 so that the manifold will flex, rather than push the cylinders 7 and 8 out of 50 alinement as the manifold heats up. A similar bend 44 is provided in the exhaust manifold 10. It will be apparent, therefore, that the portions of 55 the two manifolds which engage the cylinders 7 and 8 are not subject to as substantial a lateral movement, due to expansion, as would be the case if these manifolds pushed directly outwardly instead of being provided with an expansion bend which permits part of the expansion to be taken up by the bend. Inequalities in temperature between the inlet and exhaust manifolds and unequal expansions resulting therefrom are taken 60 up in these bent parts and stresses thereby avoided. The exhaust manifold is not heated to so high a temperature as the steam intake manifold and 65 to a certain extent the bending of the manifolds assists in preventing distortion of the cylinders 7 and 8, so as to destroy alinement of the same. The adjacent walls of the manifolds 9 and 10 are slightly spaced, as shown in Figs. 1, 2, and 3. 70 This provides a chamber 45 between the manifolds which aids in insulating the hotter steam intake manifold from the cooler exhaust manifold. The steam intake manifold is at a higher level than the exhaust manifold 10 and to a 75 certain extent, overlies the latter.

It will be apparent from the above description that my improved construction permits heat expansion within the integral cylinder block without causing excessive wear in the bearings due to misalinement. The centers of the cylinders 7 5 and 8 will be in proper alinement when heated up and, therefore, the setting up of excessive stresses is avoided. The main bearings are carried by supports formed integral with the frame 11 and are, therefore, properly alined. There is 10 not the same possibility of inaccurate adjustment, since the supports are machined directly in the frame 11. This type of support for the main bearings has the further advantage over the type having bearing caps held down with bolts that 15 there is not the possibility of the bolts becoming bent, shorn or stretched. Moreover, the axis of the bore of the supports 13 does not deviate and perfect alinement is, therefore, promoted, this being a considerable advantage over the type in 20 which the bearing cap must be tightened over the bearing.

In the embodiment of my invention shown in Figs. 1 and 2, the power take-off member, such as a gear or sprocket, may be keyed at 46 to the 25 crank shaft 27. This power take-off member is accordingly disposed intermediate the cranks 28. In the embodiment shown in Fig. 6, the frame and the steam end of the engine are identical with that shown in Fig. 2. The crank shaft 47 has a 30 crank 48 formed integral therewith. The openings 29 are identical with the openings shown in Fig. 2. Inasmuch as the second crank 28 is formed separate from the crank shaft 47, the shaft may be supported in roller bearings similarly, as in the 35 embodiment shown in Fig. 2. The cover plate 49 shown in Fig. 6, is provided with a pair of roller bearings 50 for rotatably supporting the projecting end 51 of the crank shaft 47. These roller bearings are contained within a housing 52 fitting 40 an opening in the cover plate 49. The inner races of the bearings are held in position on shaft 47 by a nut 56. The outer races may be adjusted within the housing 52 by a gland member 57, which serves also as an oil seal. The main bearing 26 is contained within a housing 58 which 45 is secured in position in the bearing support 13. The housings 22 and 52, on the other hand, may slide relative to their respective supports 13 and 49. This takes care of possible expansion, stresses 50 in the bearings and in the crank shaft. A power take-off member may be secured by the key 60 to the shaft 47 in the space 12 between the two divisions of the frame 11; and on the projecting end 51 may be secured by the key 61 or other 55 suitable means a second power take-off member. It will be apparent, therefore, that I have provided a steam engine which may be supplied with a crank shaft on which is mounted a single power take-off member, or with a crank shaft on which 60 is mounted a pair of power take-off members. In the embodiment shown in Fig. 2, this power take-off member is disposed in the space 12; in the embodiment shown in Fig. 6, one of the power take-off members is disposed intermediate the 65 cranks and the other on a projecting end of the crank shaft. The steam engine is, therefore, adapted to a variety of different driving connections.

While I have described in specific detail two 70 embodiments of my invention, it will be apparent that various additions, substitutions and changes can be made therein, without departing from this invention, and under the scope of the following claims.

What I claim is:—

1. A twin cylinder engine comprising an integral cylinder block having a pair of cylinders, one cylinder at each end of the block, inlet and outlet manifolds positioned centrally and spaced from each other, control valves between said cylinders and said manifolds and separate spaced connecting passages between said cylinders, valves and manifolds, said passageways having expansion bends to prevent twisting said cylinders out of alignment through unequal expansion of said passageways, a bearing frame having cross-head guideways alined with said cylinders when said cylinder block is at working temperatures, and bolts securing said frames to said cylinder block and being provided with clearance spaces to permit said cylinder block to contract and draw

said cylinders out of alignment with said guideways when cooled below working temperatures.

2. A twin cylinder engine comprising an integral cylinder block having a pair of cylinders, one cylinder at each end of the block, inlet and outlet manifolds positioned in said block between said cylinders and control valves between said cylinders and said manifolds, said cylinders having pistons and cross heads, a pair of spaced cross head guides, one for each cylinder, integrally mounted to aline with said cylinders when the latter are at working temperatures and offset therefrom when said cylinders are at the same temperatures said guides and bolts securing said guides to their respective cylinders and being provided with clearance spaces to permit relative movement to and from alignment.

JOHN M. SHIMER.
